(57) **CLAIM**

The ornamental design for an information apron, as shown and described.

DESCRIPTION

FIG. 1 is a perspective view of an information apron showing my new design;

FIG. 2 is a front elevational view thereof;

FIG. 3 is a rear elevational view thereof;

FIG. 4 is a side elevational view thereof; the undisclosed opposite side elevational view being a mirror image thereof; and,

FIG. 5 is a top plan view thereof.

The broken lines shown in FIGS. 1-4 represent stitching.

The broken line showing of the information card and text shown in FIGS. 1 and 2 are for illustrative purposes only and forms no part of the claimed design.

1 Claim, 2 Drawing Sheets
